MARTIN J. ERK, OF ELMIRA, NEW YORK.

BOILER.

1,050,632.

Specification of Letters Patent.

Patented Jan. 14, 1913.

Application filed April 11, 1911. Serial No. 620,317.

To all whom it may concern:

Be it known that I, MARTIN J. ERK, of Elmira, in the county of Chemung, in the State of New York, have invented new and useful Improvements in Boilers, of which the following, taken in connection with the accompanying drawings, is a full, clear, and exact description.

This invention relates to certain improvements in boilers for generating high or low pressure steam for power or heating purposes and is also adapted to be used as a generator for hot water circulating systems.

15 The main object is to produce a simple and highly efficient boiler of the character described in which water or other liquid may be rapidly converted into steam or circulated through the hot water system with 20 a minimum consumption of fuel. In other words I have sought to distribute the water or other liquid through the combustion chamber in comparatively shallow channels in such manner as to expose relatively small 25 quantities of water to relatively large heating areas without in any way complicating the work of assembling the water containing chambers or pipes within the combustion chamber.

30 These objects contemplate the use of hollow or partially hollow division walls within the combustion chamber or fire box constructed and arranged so that the products of combustion rising between them will 35 overflow downwardly around the outside, thereby practically enveloping the entire system of water heating conduits within the heating chamber and more effectively consuming the gases and other fuel products 40 before passing out through the outlet.

Another object is to utilize the upper portion of the heater as a reservoir for coal or similar fuel so that it may be fed more easily in small quantities into the combustion chamber for the purpose of maintaining a higher degree of combustion with less liability of waste of gas and other fuel products which otherwise would pass off through the outlet.

45 50 Other objects and uses relating to specific parts of the boiler will be brought out in the following description.

In the drawings—Figure 1 is a vertical sectional view of a boiler embodying the various features of my invention showing portions of the heating coils as partly broken

away and partly in section. Fig. 2 is a horizontal sectional view of a modified form of hollow partition walls and fire box, taken on the line 2—2 of Fig. 3, this view omitting the boiler setting, hollow baffle, etc., of Fig. 1, and, Fig. 3 is a transverse sectional view of the hollow partition and fire box structure shown in Fig. 2, the section being taken on line 3—3 of said Fig. 2.

65 The boiler shown in Fig. 1 comprises an outer wall or casing —1— of fire brick or other suitable material resting upon a suitable supporting base —2— and rising some distance therefrom to form an interior combustion chamber —3—. Within the base of the combustion chamber is an ash pit 4, the top wall thereof being provided with an opening and arranged at said opening and supported by the top wall of the pit is a 70 grate 5. Mounted upon the top wall of the pit 4 is a vertically disposed cylindrical member 6 which in connection with a portion of the top wall of the pit 4 and the grate 5 constitutes a fire pot, a portion of 75 the top wall of the pit 4 and the grate forming the bottom of the fire pot. Mounted within and inclosed by the member 6 is a plurality of, in this instance, two, hollow division walls —7— and —8— arranged one 80 within the other some distance apart to form an intervening fire passage —9—. These partition walls preferably consist of coils of pipe having their convolutions resting one upon the other and extending to a 85 height substantially equal to that of the fire pot —6—.

90 The outer coil —7— is of substantially the same diameter as that of the interior of the fire pot and preferably consists of a single pipe coiled upon itself in the manner shown and having its lower end connected to a return pipe —10—, while its outer end is connected to an upflow pipe —11—. In like manner the inner coil —8— consists of 95 a single pipe of somewhat smaller cross sectional diameter than that of the coil —7— and having its lower end connected to a return pipe —12— and its outer end connected to an upflow pipe —13—.

100 105 110 The lower convolution of the outer coil —7— preferably rests upon suitable bearings —14— surrounding the grate —7— and is additionally supported by its return and upflow pipes —10— and —11— which extend outwardly through openings in the inclosed wall or case —1—. In like man-

near the coil —8— is supported by its laterally extending return and upflow pipes —12— and —13— which extend through suitable openings in the outer wall or casing —1— preferably at the same sides and in proximity to the corresponding return and upflow pipes of the outer coil —7—.

By supporting the coils in the combustion chamber in the manner described, it is evident that their several convolutions may expand and contract freely without liability of straining any of the connections, each coil being entirely independent of the other so as to constitute generators for separate circulating systems. The greatest heat will, of course, be concentrated within and around the central coil —8— and the circulation of water or generation of steam will therefore be more expeditious than in the outer coil —7— particularly when it is considered that the pipes of the inner coil —8— are somewhat smaller than those of the outer coil and in some instances it may be possible to use this inner coil separately from the outer coil, as for example, when but little steam or hot water heating is required in which case the fuel would of course be placed only within the inner coil and not between the outer coils.

30 A horizontal baffle pipe-coil —15— is supported within the combustion chamber some distance above the coils —7— and —8— with its convolutions in close juxtaposition and is provided with a return flow pipe —16— and an upflow pipe —17— extending laterally through and supported in suitable openings in the wall or casing —1— for holding said coil in its operative position and permitting the convolutions to expand and contract freely without liability of overstraining the connections of its ends, the central portion of the coil being left open at —18— for permitting the entrance of fuel from the top within the coils —7— and —8— and onto the underlying grate —5—.

50 Directly above the horizontal coil —15— is a crown sheet or cover plate —19— forming the upper wall of the combustion chamber and in this instance provided with a central opening —20— having a movable lid —21— which may be opened at will to permit the entrance of fuel through the openings —20— and —18— within the underlying coils —7— and —8—.

55 The casing —1— extends some distance above the plate —19— forming a fuel reservoir —22— for the reception and retention of a limited amount of reserve fuel which may be forced into the opening —20— when the lid —21— is raised.

60 The return pipes for all of the coils are preferably arranged at one side of the heater in close proximity to each other, while the upflow pipes are arranged in close

proximity to each other at another side of the heater and in this instance are connected separately to a superposed water and steam dome or distributing head —23— having suitable distributing pipes —24— leading 70 from the upper side thereof and adapted to be connected to the radiating system for heating purposes or to an engine or other appliance requiring steam heat or power or hot water heat, said distributing head being provided with a water gage —25— and steam gage —26— for purposes well known.

75 The return pipes for the coils —7—, —8— and baffle —15— may be connected to a single return conduit —27— which in turn may be connected by a pipe —28— to the lower water containing chamber of the head —23— or may be connected by an extension —29— to a hot water radiating system and in order that the boiler may be used for either hot water or steam, the extension —29— is provided with a valve —30—, while the branch return pipe —28— from the head —23— is provided with a valve —31—.

80 When it is desired to use the boiler for generating high or low pressure steam for power or heating purposes, the valve —30— may be closed and the valve —31— opened which allows any water of condensation 95 which may return through the distributing pipes —24— to the head —23— to return through the pipes —28— and —27— to the return pipes of the coils —7—, —8— and —15—. On the other hand when it is desired to use the boiler for hot water circulation, the valve —31— may be closed and the valve —30— opened, thus permitting the water to return from the circulating system through the pipe —27— to the coils 100 after passing upwardly through the upflow pipes, distributing head and distributing pipes through the heating system.

105 In Figs. 2 and 3 I have shown a hollow liquid containing fire box —35— and a series of hollow liquid containing partitions —36— dividing the interior of the fire box into a series of fuel compartments, said partitions being preferably made of boiler iron separately from the fire box and are provided with upflow and return pipes —37— and —38— preferably leading from the upper and lower portions of their opposite ends respectively. These pipes —37— and —38— extend laterally through suitable stay tubes —39— connecting the inner and outer shells of the fire box and forming water tight joints therewith, said lateral extensions and stay tubes serving as supporting means for holding the hollow partitions in operative position within the fire box where they are entirely enveloped by the products of combustion. These partitions are used more especially 115 in heaters of rectangular form and take the 120

125 130

place of the coils —7— and —8— shown in Fig. 1. When the boiler is made rectangular in the manner described, the hollow fire box serves the same purpose as the fire box —6— of the construction shown in Fig. 1 except that it has the additional function of containing water or other liquid which it is desired to convert into steam or to circulate through a hot water heating system, in which case the fire box may be inclosed in a casing or outer shell —1— with a horizontal partition similar to the partition —19— and may also be provided with an overlying horizontal hollow baffle corresponding to the coil —15—. Otherwise the hollow partitions may be connected to the heating or circulating system in substantially the same manner as shown in Fig. 1.

What I claim is:

20 A steam or hot water boiler comprising in combination with a distributing head, an outer casing having a grate in the bottom thereof and a baffle some distance above the grate forming with the casing a combustion chamber, the latter being provided with an

outlet below the grate, a fire box within the combustion chamber spaced apart from the casing, a plurality of unconnected independent hollow liquid containing partitions dividing the interior of the fire box into a plurality of fuel compartments, each partition having an independent upflow pipe and an independent return flow pipe connected thereto and extending upwardly from the walls of the casing, the upflow pipes communicating with the distributing head, a return conduit common to the return flow pipes and to which the latter are connected, a branch return pipe connecting the return conduit with the distributing head, and valves in the return conduit and return branch pipe whereby the heater is utilized for the production of steam or hot water, substantially as described.

In witness whereof I have hereunto set my hand on this 3d day of April 1911.

MARTIN J. ERK.
